UNITED STATES PATENT OFFICE.

JAMES HOWARD, OF BOSTON, MASSACHUSETTS.

SOLE-EDGE-BURNISHING MACHINE.

SPECIFICATION forming part of Letters Patent No. 296,570, dated April 8, 1884.

Application filed December 26, 1883. (No model.)

To all whom it may concern:

Be it known that I, JAMES HOWARD, of Boston, in the county of Suffolk and State of Massachusetts, have invented certain new and useful Improvements in Sole-Edge-Burnishing Machines, of which the following is a specification.

My invention relates to that class of machines in which the boot or shoe to be operated upon is held by a jack, while the burnishing-tool and its immediate actuating mechanism are held and guided by the hand of the operator, the object of my invention being to so construct and arrange the working parts of the machine 15 that the burnishing-tool may be freely moved in every direction, so as to be adapted to burnish every part of the edge of the sole, and embodies—combining with the working-head or tool-operating part of the machine—a secondary swinging frame and a primary resilient connection, so that although the position of the head may be changed the force-transmitting belt will always be taut and in condition 20 to vibrate the burnishing-tool. I attain this object by the mechanism illustrated in the accompanying drawings, in which—

Figure 1 is a side elevation of my machine. Fig. 2 is an end elevation, showing the working-head of the machine. Fig. 3 is an elevation 30 showing the rear part of the machine, and Fig. 4 is a plan view of the tool-holder.

A' A', Fig. 3, are bearings connected to the frame A of the machine, Fig. 3, in which revolves a shaft, B. From this shaft are suspended 35 the swinging frames C and D, Figs. 1 and 3.

In the lower end of the two arms that project downward from the frame C are pointed or center screws C' C'. These screws support on their points the housing C'', Figs. 1 and 40 3. In this housing is fitted a pin or stud, (indicated by dotted lines,) C'', Fig. 3. The lower end of the stud C'' is fastened in the housing C''.

In the housings C'' is a spindle, C''. This 45 arrangement of the housing C'', stud C'', and screws C' C' forms a universal joint; admitting of free movement in a vertical or horizontal plane, so that the head of the machine can be turned to cause the burnishing-tool to bear 50 upon the edge that may be presented to its action.

C'' is an arm extending from the housing C''

to the head of the machine. From the end of this arm C'' at Fig. 2 extends a semicircular frame or fork, E, Fig. 2.

Through the bosses E' E' of the frame E are center-screws E'' E'', Fig. 1, and on these screws is supported the yoke or frame F, Figs. 1 and 2.

F'' F'' are two lugs extending from and forming a part of the frame F, in each of which is a center-screw.

H H', Fig. 2, is a frame mounted on the centering-screws F'' F''. In the upper part, H, of this frame I place a shaft centrally located, 65 which has the pulley H'' upon it, and by which it is driven. This shaft has a crank-pin, H'', which imparts a reciprocating movement to the lever K, Figs. 1 and 2. At the same time the working-head of the machine—containing 70 the crank-shaft, pulley H'', frame H H', and lever K—is capable of being rocked in a vertical plane on the center-screws F'', while the screws F'', working-head, and frame F' are all capable of being rocked in a horizontal plane 75 on the center-screws E'' of the fork E, Figs. 1 and 2. This combination of all these movements makes it much easier to guide the burnishing-tool on all styles of sole-edges with this machine than with any machine of its class 80 heretofore in use.

L, Fig. 1, is a close-coiled spring, which extends from the working-head of the machine to the swinging frame D, to which it is attached by the screw L', which forms a joint. 85 This spring prevents any slackening of the belt when the head is rocked on the screws F'', and also through its being an elastic connection between the head and frame D it does not interfere with the free movement of the head 90 (within reasonable limits) in every direction.

M is the burnishing-tool, and N, Fig. 4, the tool-holder. This tool-holder N is pivoted to a center piece, P, (see Fig. 4,) attached to the vibrating lever K, Figs. 1 and 2, and has two 95 tool-holding sockets, P' P'', Fig. 4.

Motion is communicated to the crank-shaft H'' in the head of the machine through the pulley H'' by the belt D', which passes around the pulley D'' and is guided by the pulleys 100 D'' D''.

The tool-holder N, Figs. 1 and 2, is locked into position by means of the lever P'', Fig. 2, the lower end of which fits into one of the

notches P' or P^2 , Fig. 4, the lever being pivoted on the screw P^4 , Fig. 2.

To change the position of the tool-holder N it is only necessary to press the lever P^3 , and 5 then to turn the tool-holder to the position desired, and push the lever P^3 back into place.

R , Fig. 1, is a handle, by which the operator guides the machine in its work.

Having thus described my invention, what I 10 desire to secure by Letters Patent is—

1. In a sole-edge-burnishing machine, the combination of the swinging frame D , arm C^5 , resilient connection L , and working-head with the belt D^4 , pulleys D^2 D^3 , and driving-pulley 15 D' , all operating together substantially as described, and for the purpose set forth.

2. In a sole-edge-burnishing machine, the combination of the swinging frames D and C , the housings C^2 and C^6 , spindle C^4 and arm C^5 , and working-head of machine, all operating together substantially as described, and for the purpose set forth. 20

3. In a sole-edge-burnishing machine, the combination of the working-head having a crank-shaft, H^3 , lever K , tool-holder N , and locking-lever P^3 , all operating together substantially as described, and for the purpose set forth. 25

JAMES HOWARD.
